UNITED STATES PATENT OFFICE.

WARREN W. PERKINS, OF NORWOOD, OHIO.

BUFFER MECHANISM.

No. 902,601.

Specification of Letters Patent.

Patented Nov. 3, 1908.

Application filed October 21, 1907. Serial No. 398,434.

To all whom it may concern:

Be it known that I, WARREN W. PERKINS, a citizen of the United States, residing at Norwood, in the county of Hamilton and State of Ohio, have invented certain new and useful Improvements in Buffer Mechanism, of which the following is a specification.

My invention relates to buffer mechanism and I have exemplified the same as employed on a gage lathe of the character used in working wood and the like, and it has for its object the providing of a buffer in such manner that the carriage in its return may be arrested with an easy motion for avoiding jar to the parts.

Figure 1 shows a front elevation of a gage lathe embodying my invention. Fig. 2 is a rear elevation of the same. Fig. 3 is a front elevation of the cushioning part showing the same in connected relation. Fig. 4 is a similar view showing the cushioning chamber in longitudinal section on a line corresponding to the line $x-x$ of Fig. 5, showing the parts in collapsed relation in full lines and in distended relation in dotted lines. Fig. 5 is a cross - section on a line corresponding to the line $y-y$ of Fig. 4, and, Fig. 6 is a detail of the carriage on the line $z-z$ of Fig. 1.

In machines of the character to which my invention is principally applicable there is usually a feed-screw employed for causing the advance or cutting travel of the carriage, at the end of which movement the engagement between the nut on the carriage and the feed-screw is released for permitting the carriage to return quickly to initial position under pulling stress of a weight suitably connected with the carriage.

In gage lathes as heretofore constructed, it has been found necessary by the operator to manually retard the return of the carriage by pressing his hand against the same for holding it against the pull of the weight in order to ease the jar at the end of the return of the carriage, the jar being occasioned by the striking of the carriage against the tail-stock or other part provided on the lathe for limiting its return. This employment of the hand was a tiring operation and interfered with the proper handling of material and rapid operation of the lathe, as it consumed moments of time which could be better employed in the manipulation of material or operating parts of the

lathe. While this manual retarding of the carriage aided somewhat in relieving the jar, it has been found in practice that sufficient pressure could not be exerted to overcome the jar while employing a weight or other return agency which would return the carriage to initial position with sufficient rapidity for practical operation. I obviate these difficulties by providing means whereby the carriage may be returned to initial position with great rapidity. During the final portion of the return movement of the carriage I subject it to a counter pressure, preferably an air pressure, which quickly slackens the speed of return movement of the carriage and causes it to come to rest with an easy motion, and in practice relieving the stoppage of the carriage of jar and relieving the operator of the duty of attention to the stoppage of the carriage on its return movement, thereby permitting the operator to give his attention to the manipulation of the material and the advance travel of the carriage for cutting the material, with the result that the life of the machine is lengthened and its capacity enhanced. My improved device enables me to employ a quicker return.

1 represents the bed of the lathe and 2 is the carriage which travels longitudinally of the bed on ways 3, the carriage extending across the top of the bed in usual manner.

4 is the head-stock in which a suitable head-spindle 5 is journaled and rotated in 90 suitable manner.

6 is the tail-stock which carries a usual tail-spindle 7, the material or stock 8 being supported and rotated between the spindles.

10 is a feed-screw journaled in suitable 95 bearings 11 and operated in suitable manner.

12 are ordinary half-nuts mounted for movement in the apron 13 of the carriage and having pivotal connection, as at 14, 100 with a double-throw lever 15 secured to a rock-shaft 16 having a lever 17 thereon. In the construction shown, when the lever 17 is swung downwardly, the half-nuts are released from the feed-screw, and when the 105 said lever is swung upwardly said half-nuts are connected with the feed-screw.

18 is an operating lever pivoted at 19 to the carriage and having an arm 20 provided with a bolt 21 movable in a slot 22 of a link 110 23 pivoted at 24 to the lever 17.

25 is a depending arm swinging on a pivot

26 on the carriage. This arm has a lug 27 thereon adapted to have engagement made therewith by a lug 28 on the lever 17, a spring 29 secured to the arm and lever 17 normally urging the lug 27 into the path of travel of the lug 28. The arm 25 also has a lug 30 thereon upon which the lever 17 may rest when the half-nuts are disengaged, these half-nuts being engaged with the feed-screw when the lugs 27 28 are in engagement.

31 is a tappet which is adjustable along the bed, the arm being adapted to strike the tappet for causing the lug 28 to be pushed 15 out of range of the lug 27 and thereby causing the lever 17 to swing downwardly for opening the half-nuts and releasing the carriage, the moment of release being determined by the position of the tappet lengthwise of the bed. As soon as the carriage is 20 released it is brought under the influence of a returning agency shown as a weight 32 attached to a belt 33 secured to the carriage at 34 and passing over a pulley 35 on the bed and over suitable pulleys 36 37.

The carriage has a gage-knife or cutting tool 40 secured in a gage-knife support 41 pivoted on a stud 42 on the carriage, the support having a finger 43 which engages a 30 gage-plate 44 suitably secured to the bed and formed with a contour according to the shape it is desired to give the material being turned. There may be one or more of these gage-knife supports. If desired the cutting 35 of these tools may be supplemented by a back-knife 45 adjustably secured to a back-knife slide 46 movable up and down in ways 47 of an upright frame 48 secured to the bed, the back-knife slide being caused to 40 move up and down by having a diagonal slide-way 49 thereon with which a guide-block 50 on the carriage engages. In order to prevent binding of the slide in the upright frame and to counter-balance the same, 45 the slide is at each end provided with a rack 51 with which pinions 52 engage, the pinions being on a shaft 53 journaled in bearings 54 of the upright frame and having counterpoise sheaves 55 56 secured thereto, 50 straps 57 58 having one of their ends secured to said respective sheaves and being provided with suitable weights for counter-balancing the upright frame.

61 is a chamber shown as a cylinder in 55 which a piston 62 is adapted to reciprocate. A piston-rod 63 is secured to the piston and is guided in a bearing 64 of the head 65 of the chamber. The piston-rod is preferably prevented from turning, for accomplishing 60 which I have shown the piston-rod with its bearing as of rectangular cross-section.

The piston-rod has an arm 66 pivoted thereto as through the medium of a yoke 67 secured to the piston-rod and carrying the 65 pivot 68. The arm has a hook 69 thereon

adapted to engage with a keeper 70 on the carriage, this keeper being shown on a plate 71 secured to the carriage.

72 is an inclined way shown on a lug 73 on the chamber, the inclined way being 70 adapted to be engaged by the arm 66 in rear of its pivot for causing disengagement between the hook and keeper. I have shown the rear end of the arm 66 provided with an anti-friction roll 74 adapted to ride on the 75 inclined way, the arm being provided with an upward bow 75 for clearing the lug 73. The outer end of the piston-rod is adapted to be received by a recess 76 in the plate 71, the recess preferably having a tapered wall 80 77 for centering the piston-rod.

When the carriage is at the beginning of its advance travel or cutting movement, the hook and keeper are in engagement. When the carriage begins to travel in its cutting 85 movement under the influence of the feed-screw, the piston-rod, being engaged with the carriage, is moved with the carriage for drawing out the piston-rod, the roll 74 riding on top of the chamber. This movement 90 continues until the roll 74 has traveled upwardly on the incline 72 as shown in dotted lines in Fig. 4, thereby disengaging the hook and keeper and releasing the engagement between the piston-rod and carriage, the carriage continuing its travel disengaged from the piston-rod. When the cutting movement has been accomplished and the half-nuts released from the feed-screw, the carriage is quickly returned to initial position under 100 the influence of the weight 32, the carriage, through the plate 71 thereon, striking the end of the piston-rod and compressing the air to rear of the piston in the chamber which forms a cushion for the carriage. The 105 cushion is released by providing the chamber with a suitable opening communicating therewith, which I accomplish through the stop-cock 78, through which the rapidity of release of the cushion may be regulated, 110 thereby bringing the carriage to an easy stop and providing a cushion for preventing jar upon the return of the carriage. I also preferably provide the forward end of the chamber with suitable openings 79 80, the 115 opening 80 being preferably in rear of the piston, but closely adjacent thereto for relieving suction upon the piston when it is withdrawn to its limit.

Having thus fully described my invention 120 what I claim as new and desire to secure by Letters Patent is:

1. In buffer mechanism, the combination, with a bed, a carriage movable longitudinally thereon, means for advancing said carriage, and means for causing quick return of said carriage, of a cushion for said carriage for cushioning said return comprising a chamber-member and a piston-member therefor, and means connecting 130

- with one of said members for distending said members by the movement of said carriage, one of said members provided with an inclined way acting on said last-named 5 means for releasing said connection.
2. In buffer mechanism, the combination, with a bed, a carriage movable longitudinally thereon, means for advancing said carriage, and means for causing quick return of said carriage, of a cushion for said carriage for cushioning said return comprising a chamber-member and a piston-member therefor, a regulating valve for said chamber-member, and means connecting 10 with one of said members for distending said members by the movement of said carriage, one of said members provided with an inclined way acting on said last-named 15 means for releasing said connection.
3. In buffer mechanism, the combination, with a bed, a carriage movable longitudinally thereon, means for advancing said carriage, and means for causing return of said carriage with a quick movement, of cushioning means for said carriage for cushioning said return comprising a chamber-member and a piston-member therefor, releasable connecting means for one of said members for distending said members upon 25 advance of said carriage, said connecting means comprising a hook and a keeper therefor, and a lever on which one of said last-named parts is mounted, said lever pivoted to said piston-member, and said chamber-member having a lug thereon upon 30 which said lever rides for releasing engagement between said hook and keeper between the ends of advance movement of said carriage.
4. In buffer mechanism, the combination 40 of a cushion-member, a piston therefor, a piston-rod secured to said piston, a lever pivoted to said piston-rod, and connecting means between said lever and a pulling part, said lever having a rearward extension and said chamber having an inclined way thereon with which said extension is arranged to contact for releasing the connection between said lever and pulling part, substantially as described. 45
5. In buffer mechanism, the combination 50 of a cushion-chamber, a piston therein, a piston-rod for said piston, a lever pivoted to said piston-rod, a pulling part, said pulling-part and piston-rod having a recess between them for relatively positioning the same, releasable connecting means between said lever and pulling-part operative during initial pulling movement of said pulling-part, and means for causing release in said connecting means upon further pulling movement of said pulling-part, substantially as described. 55
6. In buffer mechanism, the combination 60 of a cushion-chamber, a piston having movement therein, a piston-rod therefor, a catch on said piston-rod, means for releasing said catch, said chamber having openings in advance of said piston and a regulating valve for said chamber to rear of said piston, substantially as described. 65

In testimony whereof I have subscribed my name hereto in the presence of two subscribing witnesses.
